UNITED STATES PATENT OFFICE.

HENRY B. COATS, OF Veedersburg, Indiana.

DESIGN FOR A SOLID RUBBER TIRE FOR MOTOR-TRUCKS AND THE LIKE.

59,717.

Specification for Design.

Patented Nov. 22, 1921.

Application filed February 14, 1921. Serial No. 445,008. Term of patent 14 years.

To all whom it may concern:

Be it known that I, HENRY B. COATS, a citizen of the United States, residing at Veedersburg, in the county of Fountain and State of Indiana, have invented a new, original, and ornamental Design for a Solid Rubber Tire for Motor-Trucks and the like, of which the following is a specification,

reference being had to the accompanying drawing, forming part thereof.

The figure is a perspective view of a tire showing my new design.

I claim:

The ornamental design for a solid rubber tire for motor-trucks and the like, as shown.

HENRY B. COATS.
